UNITED STATES PATENT OFFICE.

HENRY B. BUCKHAM, OF CHICAGO, ILLINOIS, ASSIGNOR TO DUOPHONE MANUFACTURING CO., OF CHICAGO, ILLINOIS, A COPARTNERSHIP.

DESIGN FOR A CABINET FOR TONE-REPRODUCING DEVICES.

Application filed February 16, 1922. Serial No. 731. Term of patent 3½ years.

To all whom it may concern:

Be it known that I, HENRY B. BUCKHAM, a citizen of the United States, residing at Chicago, in the county of Cook and State of Illinois, have invented a new, original, and ornamental Design for a Cabinet for Tone-Reproducing Devices, of which the following is a specification, reference being had to the accompanying drawings, forming part thereof.

The figure is a perspective view of a cabinet for tone-reproducing devices, showing my new design.

I claim:

The ornamental design for a cabinet for tone-reproducing devices, as shown.

HENRY B. BUCKHAM.
